United States Patent

Des. 235,585
Patented June 24, 1975

235,585

COT-TENT

Dale W. Stevens, 3998 Oliver Drive,
Salt Lake City, Utah 84117

Filed Sept. 14, 1973, Ser. No. 397,254

Term of patent 14 years

Int. Cl. D21—04

U.S. Cl. D88—3 B

FIG. 1

FIG. 2

FIG. 3

FIG. 4

FIG. 5

FIG. 6

FIG. 7

FIG. 1 is a perspective view of a cot-tent showing my new design;

FIG. 2 is a top plan view;

FIG. 3 is a left end elevational view;

FIG. 4 is a right side elevational view;

FIG. 5 is a bottom plan view;

FIG. 6 is a right end elevational view; and

FIG. 7 is a left side elevational view.

I claim:

The ornamental design for a cot-tent, substantially as shown and described.
